FOREIGN PATENT DOCUMENTS

WO DM082156 7/2013

Primary Examiner — Katie Jane Stofko

(74) *Attorney, Agent, or Firm* — The Keys Law Firm, PLLC

(57) **CLAIM**

The ornamental design for a bear shaped gummy, as shown and described.

DESCRIPTION

FIG. 1 is a front, top and left side perspective view of a bear shaped gummy, showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines, and the area within the broken lines, depict portions of the bear shaped gummy that form no part of the claimed design.

1 Claim, 7 Drawing Sheets
